EXPLOSION-PROOF LIGHTING UNIT

Ernest H. Benson, Kansas City, Mo., assignor of one-fourth to John A. Benson, one-fourth to Arthur A. Benson, one-eighth to John E. Benson, one-eighth to Robert H. Benson, one-eighth to William F. Benson, and one-eighth to Edward L. Benson, all of Kansas City, Mo.

Application May 21, 1942, Serial No. 443,861

2 Claims. (Cl. 240—11.2)

My invention relates to a novel construction of an explosion-proof lighting unit and relates more particularly to a construction which provides a strong, rugged unit and one in which the parts are so assembled as to form a pressure-tight unit.

In factories and manufacturing plants frequently the atmosphere contains explosive vapors. Under such conditions, the lighting units must be protected as failure or breaking of a heated bulb may ignite the vapors resulting in an explosion or fire. The usual practice has been to enclose the bulb in a housing which has a thick lens through which the light is to be projected. Such a unit must have vapor-tight joints to prevent explosive vapors from entering the housing.

It is further desirable and necessary to have the unit rugged in order to withstand abuse since workmen oftentimes inadvertently strike the unit with tools or machinery. It is also important that such a unit be light in weight since it is sometimes suspended on a flexible cord and used as a drop light.

There are definite specifications stipulated by the Fire Underwriters requiring that light units of this character pass certain rigid tests. For instance, the housing must withstand 500 pounds per square inch hydraulic pressure without rupture or failure of the joints. Small units utilizing relatively low candle power can be built to withstand this pressure but, to my knowledge, no satisfactory unit of a thousand-watt capacity has been produced. Standard modes of construction used in smaller capacity lighting units have failed to meet the rigid requirements imposed.

The salient object of my invention is to provide a large size, explosion-proof lighting unit that is sufficiently rugged to pass the required tests.

In brief, my invention comprises a housing for a high capacity light bulb having a thick, tough pressure-resistant transparent lens removably held in an opening in the housing by pressure gripping elements.

In the drawing forming a part of this specification and wherein like numerals are employed to designate like parts throughout the same,

Fig. 1 is a front elevation of an explosion-proof lighting unit embodying my invention, parts being broken away for clearness of illustration,

Fig. 2 is a fragmentary bottom plan view of the unit,

Fig. 3 is a fragmentary vertical sectional view, taken on the line 3—3 of Fig. 1,

Fig. 4 is a transverse sectional view taken on the line 4—4 of Fig. 1, and

Fig. 5 is a view similar to Fig. 3 but showing a modified lens construction.

In the drawing, wherein is shown a preferred embodiment of my invention, the numeral 10 designates a housing for a light bulb 11. The unit here shown is adapted to enclose a bulb of at least a thousand watts. The housing, preferably made of aluminum or alloys of aluminum or magnesium is generally bell-shaped to conform with the shape of the light bulb and to provide ample space between the housing and bulb. Vertical fins 10a are provided on the outer surface of housing 10 to dissipate heat created by the bulb 11. For mounting the bulb 11 within the housing I provide a socket 12 into which the bulb is threaded. The socket 12 is suspended within the housing 10 by a bracket 13. A junction box 14 threaded on the reduced upper end of housing 10 retains an insulating block 15. Screwed into the upper end of the junction box 14 is a pipe 16 which hangs from the ceiling and froms a conduit for electrical conductors 17 and 18. The ends of conductors 17 and 18 connect with terminals 19 and 20 carried by an insulating bar 21, secured to support 14a integral with junction box 14. A removal plug 22 in the junction box permits easy access to the terminals 19 and 20. Suitable conductors 23 and 24 connect terminals 19 and 20 with the light bulb 11.

Into an opening in the lower end of housing 10 and abutting shoulder 10c is screwed a soffit ring 25. A tool may be inserted through an opening 10b in housing 10 to engage gear teeth 25a on the soffit ring for tightening the ring. A spanner wrench may also be used against lugs 25b on the bottom of the soffit ring to tighten or loosen the same.

A heavy rugged transparent lens of glass, quartz or transparent plastic 26 fits within the soffit ring and is supported by a radial flange 25c. Filling the annular space between the lens 26 and soffit ring 25 is a relatively soft metal rim 27 of solder, lead, babbitt, white metal alloys or the like. The soft metal of rim 27 forms a buffer between the soffit ring and lens compensating for slight distortion at the joint and movement caused by differences in the coefficients of expansion of the parts from temperature irregularities. An outer ridge on the rim fits within a groove in the soffit ring and edges of the rim overlap beveled edges of the lens to securely re-

tain the lens within the rim and soffit ring. A spherio-parabola reflector 28 supported within the housing by brackets 29 surrounds light bulb 11 and directs light through lens 26.

The construction employing a soft metal rim on the lens and a soffit ring is generally satisfactory for small explosion-proof lighting units; but, when a light source of a thousand-watt capacity is necessary, the housing and lens joint must be designed to withstand the conditions specified. When a conventional aluminum housing of this size is exposed to the required tests, it frequently fails and is inadequate structurally. I have found, however, that if a hard metal holding band 30 is placed exterior of the housing in a position to circumscribe and surround the joint between housing 10 and lens 26, a pressure-tight joint is assured. The holding ring, preferably made of steel, has a diameter which makes a press fit with the skirt or rim of the housing. As the holding ring is pressed into place, it exerts a wedging or constricting action upon the housing and the relatively soft materials of the housing, soffit ring and lens rim yield sufficiently to assure vapor-tight joints.

A plano-convex fresnel type lens 31 is supported below lens 26 by a spun retainer ring 32. The control lens 31 concentrates the light from bulb 28 and pigment fired into the lens eliminates glare and assures low surface brightness without objectionably reducing the intensity of the light.

A wire lens retainer hanger 33 is attached to the housing to support the lenses 26 and 31 when they are removed for servicing.

In Fig. 5, I show a modified type of lens wherein the transparent lens 26 and control lens 31 shown in Figs. 1 and 3 are formed as a single unit, providing a composite lens 34. The lens 34 is formed thicker than lens 26 in Fig. 1 and the bottom surface thereof is cut to form prisms which control the light rays in the manner of lens 31.

It may thus be seen that I have accomplished the objects of my invention. The soffit ring 25 surrounds and supports lens 26. The joints between the lens and the soffit ring and between the soffit ring and the housing are concentrically disposed in the same plane. In the past, the

threaded union between the housing and the soffit ring of large units has opened as a result of a blow or under pressure sufficiently high to disrupt the housing. Since all of the joints that can open to

admit vapors into the housing are concentrically disposed in the same plane, I surround the housing with a hard steel holding band which circumscribes the joints. The holding band must be pressed onto the rim of the housing. The pressure exerted by the band wedges the housing, lens and soffit ring into a pressure-tight joint.

Actual tests have demonstrated that a unit constructed in this manner is much stronger and more rugged than any unit heretofore developed.

It is to be understood that the forms of my invention herewith shown and described are to be taken as preferred examples of the same and that various changes in the size, shape and arrangement of parts may be resorted to without departing from the spirit of my invention or the scope of the appended claims.

Having thus described my invention, I claim:

1. In an explosion-proof lighting unit, a housing, a light source in the housing, a rugged transparent lens fitted into the opening in the housing, a relatively yieldable joint between the lens and housing including a rim bounding the edge of the lens, means including a soffit ring for retaining the lens in place in the housing and a holding band exterior of the housing circumscribing the joint between the housing and lens, said band having a press fit with the housing and adapted to wedge the lens, soffit ring and rim into a pressure-tight joint.

2. In an explosion-proof lighting unit of the type including a relatively thin metal housing, a soffit ring threaded into the lower end of the housing and a lens retained within the ring by a soft metal, the improvement comprising strengthening the unit without appreciably increasing its weight by means of a rigid holding band exterior of the housing, said band circumscribing the joint between the housing and soffit ring and having a pressed fit with the housing whereby to compress it sufficiently to render said joint vapor tight.

ERNEST H. BENSON.
